UNITED STATES PATENT OFFICE.

HARRY U. TRUE, OF BRIGHTON, MASSACHUSETTS.

GOLF-TEE.

1,142,997.

Specification of Letters Patent. Patented June 15, 1915.

Application filed March 19, 1915. Serial No. 15,584.

To all whom it may concern:

Be it known that I, HARRY U. TRUE, a citizen of the United States, residing at Brighton, county of Suffolk, Commonwealth 5 of Massachusetts, have invented certain new and useful Improvements in Golf-Tees, of which the following is a specification.

This invention relates to golf tees and particularly to a portable tee adjustable to 10 a great variety of different heights and capable of construction of inexpensive material so that the tee may be abandoned after the drive, thus avoiding the trouble and delay of recovery as is necessary with any- 15 thing but a most inexpensive device.

The tee, while physically a small element in golf is a feature of increasing importance and the development of the game acquires a considerable element of personality 20 and bears a most important relation to individual style. This owing to the fact that each individual tends to play his ball at a certain height which he has ascertained to be most satisfactory to himself and his general game or to some special height under 25 some particular circumstances or places. This accounts for the survival of the "sand box" and the troublesome practice of tee molding by hand.

30 It has been attempted to produce portable "mechanical" tees which would obviate the necessity of the dirt tee, but such devices have either been nonadjustable or incapable of adaptation to the individual game, form 35 or style of play or not adapted to the practical conditions of the same or too expensive for the purpose.

In my present invention I have provided 40 a means having all of the desired features effectively combined to produce the desired result and through elements at once simple and inexpensive. In the embodiment herein shown my tee consists of a ball seat, and a support vertically adjustable by flare or 45 spread, provision being made both for preventing undue flare and for suitable vertical rigidity.

For the purposes of my present application I shall show and describe a form found 50 practical and satisfactory both from the viewpoint of the player and the manufacturer.

Throughout specification and drawing like 55 reference numerals are employed to indicate corresponding parts and in these drawings:

Figure 1 is an elevation of a tee in ac-

cordance with my invention showing a golf ball teed thereon at substantially maximum height for the given size of tee. Fig. 2 is a vertical section through the tee at about the 60 height shown in Fig. 1. Fig. 3 is a development of the tee blank and indicating the crimps in dotted lines. Fig. 4 is a view similar to Fig. 1 showing the tee adjusted to a lower elevation. Fig. 5 is a view showing the tee adjusted on sloping or uneven ground, and Fig. 6 is a view illustrating the ground gripping action of the serrated basal margin of the tee.

The tee thus illustrated is preferably 70 given the form of a hollow truncated cone 1 and is preferably produced from a flexible material such as paper which may be suitably waterproofed and colored, as for example, green, in order to make the litter in- 75 conspicuous.

The tee 1 is developed from the blank shown in Fig. 3 as an inclosing wall open at the top and bottom and expansively flaring toward its base. The wall is radially 80 crimped or corrugated as indicated at 2 from its top to its base whereby to stiffen it in the direction of its length and give to it a vertical adjustability of great scope so that a ball can be teed at just the right 85 height for the individual player or the particular place, and has an inturned uncrimped flange 3 at its top providing a flat ball seat. The basal ends of the corrugations 2 extend as a downwardly directed circumferential 90 series of ground engaging "serrations" 4 which tend to sink into the ground G (see Fig. 6) under the weight of the ball 5, or as the tee spreads laterally in adjusting it for height, whereby to firmly anchor the 95 tee and prevent displacement thereof by wind, slight vibrations or the like. The tee is of course displaced in driving and is intended to be abandoned after the drive.

The tee of the present invention lends it- 100 self particularly to the individual game, style or "form" of the player. I have illustrated in Figs. 1 and 4, only two of the numerous positions of vertical adjustment possible with it. The position of Fig. 4 is 105 reached by simply distending the cone by the application of a slight pressure vertically downward. This not only positions the ball closer to the ground but has the effect of driving the teeth-like basal ends 4 of 110 the corrugations deeper in the ground. This stiffens the tee and counteracts the loss due

to flattening of the corrugations. The position of Fig. 1 represents simply the normal distention of the cone under the weight of the ball.

5 Fig. 5 illustrates the engaging action where the tee is made on a sloping surface, as on slightly uneven ground. In this view, one side of the tee is spread laterally to a greater degree than the opposite side so as 10 to maintain a substantially horizontal ball seat and at the same time properly anchor the tee in position.

In Fig. 6 I have attempted to illustrate 15 the ground gripping action of the pointed basal ends 4 of the corrugations. These ends enter into the ground when the tee is set up and provide a circumferential series of 20 uniformly effective engaging devices adapted to firmly anchor the tee with its ball seat disposed at practically any desired elevation 25 from the ground and in a uniformly horizontal plane.

The ball seat 3 itself yields downwardly 30 slightly under the weight of the ball. This 35 has the effect of "cradling" the ball and prevents the ball rolling off the tee but does not in any way interfere with the drive. The stressing of the seat 3 under the weight of the ball also makes the tee more rigid at 40 whatever elevation it may have been adjusted.

In practice, a golfer provides himself 35 with a number of the tees and uses one at the beginning of play for each hole. The tees are so inexpensive that it is contemplated a tee shall be abandoned after each drive. The tees may be packed in any convenient form for carrying in the pocket or otherwise, or may be used with an automatic 40 vending machine.

Various modifications in the form and

construction of my device may obviously be resorted to within the limits of the appended claims.

What I therefore claim and desire to secure by Letters Patent is:

1. A golf tee comprising a flexible vertically corrugated wall and open at top and bottom.

2. A golf tee comprising a flexible vertically corrugated wall and open at top and bottom and an uncorrugated rim inturned about the opening at the top.

3. A golf tee comprising a supporting wall having an internal ball seat depressible under the weight of a ball to prevent the ball rolling off its seat.

4. A golf tee comprising a supporting wall having an internal continuous rim at its top providing a ball seat, said rim depressible to a plane slightly below the top under the weight of a ball and providing a cradle like seat effective to prevent the ball rolling off the rim.

5. A golf tee comprising an integral supporting wall having an expansible base permissive of the vertical adjustment of the height of the tee.

6. A golf tee comprising an integral supporting wall having an expansible base permissive of the vertical adjustment of the height of the tee and means for anchoring the base.

7. A golf tee comprising a substantially non-expansible ball seat and a flaringly adjustable support for said seat.

In testimony whereof I affix my signature in presence of a witness.

HARRY U. TRUE.

Witness:

MARION C. HOBBS.
